UNITED STATES PATENT OFFICE

2,623,452

POTTERYWARE DECORATING APPARATUS
STAMP

Walter H. Emerson, deceased, late of Liverpool Township, Columbiana County, Ohio, by Elizabeth King Emerson, executrix, East Liverpool, Ohio, assignor to The Homer Laughlin China Company, Newell, W. Va., a corporation of Delaware

Original application June 26, 1943, Serial No. 492,347. Divided and this application December 20, 1949, Serial No. 134,008

8 Claims. (Cl. 101—41)

1

This invention relates to potteryware decorating apparatus, and more particularly to apparatus for stamping decorations on articles of dinnerware. This application is a division of my pending application, Serial Number 492,347, filed June 26, 1943, now Patent No. 2,493,953.

The customary way of stamping decorations on dinnerware is by hand. Thus, a workman holds in his hand a rubber stamp which carries a short segment of the circular design that is to be stamped on a piece of ware. He inks the stamp and then presses it against the ware. This operation is repeated as he rotates the ware until enough segments of the design are printed to complete a circle. If another circular design is desired at the center of the ware, the step-by-step process must be repeated again. It will be seen that such a method is very slow and requires skilled labor to match the sections of the design, to make the design circular, and to print the design clearly without smearing it.

It is among the objects of this invention to provide potteryware decorating apparatus which stamps a complete design on a piece of ware in a single operation, which simultaneously stamps both brim and center designs, which accurately positions designs on the ware, which is automatic, which is rapid in operation, and which does not require a skilled attendant.

In accordance with this invention a design may be stamped on the center of a piece of ware as well as on its brim portion by forming each stamping member from a pair of coaxial stamps one of which is movable axially of the other. During inking, the decorating surfaces of the two stamps are disposed in substantially the same plane, after which the inner stamp projects from the outer one for stamping the center of the ware at the same time that the outer stamp stamps the marginal portion thereof. During stamping, the outer stamp may be flexed to conform it to the inclination of the surface that it is to decorate.

The preferred embodiment of the invention is illustrated in the accompanying drawings in which Fig. 1 is a front elevation of my machine with the stamps raised; Fig. 2 is a vertical section with the stamps lowered; Fig. 3 is an end view taken on the line III—III of Fig. 1; Fig. 4 is an enlarged horizontal section taken on the line IV—IV of Fig. 1; Fig. 5 is an enlarged fragmentary plan view of the reciprocating slide taken on the line V—V of Fig. 1; Fig. 6 is a vertical transverse section taken on the line VI—VI of Fig. 5; Fig. 7 is an enlarged vertical section through a stamping member engaging the inking

2

member; and Fig. 8 is a similar view of the stamping member engaging a dinner plate to decorate it.

Reference will now be made to the drawings. 5 Mounted on the elongated rectangular top of a table 1 are four brackets 2 that support the ends of a pair of laterally spaced parallel guide rails 3 extending lengthwise of the table. A long, narrow rectangular slide 4 between these bars is provided with laterally projecting slotted shoes 5 that straddle the rails and support them for reciprocation lengthwise. Additional brackets 6 support the rails between their ends. Projecting from the bottom of the slide near its center is a bearing 7 that is pivotally connected by a link 8 to the upper end of a lever 9 which is oscillatably mounted at its lower end in a bearing 10 fastened to a plate 11 near the bottom of the table. In order to reciprocate the slide, the central portion of the lever is provided with a laterally projecting roller 13 that travels in a cam groove 14 in the front side of a circular cam disc 15. This cam is rigidly mounted on a horizontal cam shaft 16 one end of which is journaled in a bearing 17 (Figs. 3 and 4) fastened to a vertical plate 18 extending across the back of the table. The other end of the shaft extends through a bearing 20 mounted on the side of a vertical member 21 near the center of the table. The front end of the cam shaft extends into a gear reduction unit 22 that is driven by a pulley 23 and belt 24 from an electric motor 25 mounted on base plate 11. The cam groove is shaped so that the slide is held motionless for a short time at each end of its stroke.

30 Mounted on each end of the slide is a ware-supporting member in the form of a horizontal chuck 27 the annular wall of which is rubber or other suitable resilient material. The center of the chuck has a passage opening into the upper end of a vertical pipe 28 on which the chuck is rigidly mounted. The pipe extends down through the slide and is supported by a coupling 29 secured to the bottom of the slide. As shown in Fig. 1, the coupling is connected by a flexible hose 30 to a horizontal pipe 31 that is connected to a suitable source of suction (not shown). Pipe 31 is rigidly mounted in a pair of brackets 32 on top of the table beneath one side of the slide. The upper ends of the brackets are provided with non-circular passages in which a bar 35 is slidably mounted. The center of the bar has a depending lug 36 that actuates a slide valve 37 on the pipe. The valve preferably is of the type known as Quik-as-Wink. The ends of the bar are provided

with upwardly projecting pins 38 which are adapted to be alternately engaged by a depending lug 39 on the bottom of the reciprocating slide. Thus, when the slide moves in one direction it strikes one of the pins and moves the bar to open the valve, thereby reducing the air pressure between the chuck and a piece of ware, such as a plate 41, on the chuck. This draws the plate down tightly onto the chuck and holds it there against displacement during stamping. After the slide has moved a predetermined distance in the opposite direction, lug 39 engages the other pin and moves the bar to close the valve. A similar valve and actuating mechanism are mounted on the opposite side of the table for controlling the suction of the other chuck.

Just before the valve is opened, the plate is centered on the chuck by three vertical centering pins 50 mounted on the ends of arms 51, shown best in Figs. 5 and 6. The opposite ends of the arms are pivotally mounted on the upper ends of pins 52 secured to the top of the slide at equally spaced intervals around the chuck and at uniform distances from its axis. Rotatably mounted on each pin below the arm is a roller 53 that projects into a peripheral groove in a horizontal ring 54. The ring is rotatably supported by the rollers. The pivoted end of each arm has a bifurcated lateral projection 56 that straddles a pin 57 projecting from the top of the ring. It will thus be seen that if the ring is turned, pins 57 will swing the arms and cause the centering pins either to engage and center a plate mounted on the chuck or to move away from the chuck, depending upon which way the ring is turned.

For turning the ring, a pin 60 projects from its bottom and down through a slot 61 in the slide and into one end of a push rod 62 that is reciprocable in a bearing 63 pivoted to the bottom of the slide, as shown in Fig. 6. This rod extends transversely of the slide, and its outer end carries a block 64 to the bottom of which a roller 65 is attached. The roller is urged outwardly into engagement with a cam bar 67 by a bell crank 68 pivotally connected to the bottom of the slide. One arm of the crank has a bifurcated end that straddles pin 60 above the push rod, while the other end of the crank is connected by a coil spring 69 to a pin 70 projecting from the bottom of the slide. The crank is biased in a direction that pushes rod 62 toward the cam bar and that will rotate the centering ring in a counter-clockwise direction to swing the centering pins inwardly when roller 65 runs off the cam bar. The distance that the centering pins can be moved inwardly is controlled by a set screw 72 mounted in a threaded member 73 secured to the adjacent end of the slide. The inner end of this screw is engaged by a lug 74 on the bell crank after the latter has rotated the desired amount.

The cam bar 67 is rigidly mounted on top of a block 75 that is slidable transversely of the table in a guide member 76 attached to one of the brackets 2 below the front guide rail 3. A screw 77 is journaled in the bracket 2 and is threaded through block 75 so that by turning the screw the cam bar can be moved toward or away from the center of the table in order to cause the centering pins to swing outwardly to a greater or lesser extent. The inner end of the cam bar is inclined outwardly so that roller 65 will roll off the bar and permit spring 69 to move the centering pins inwardly. This centers a plate on the chuck. Immediately thereafter the cam roller engages another cam 78 (Fig. 5) which causes the centering

pins to be moved outwardly again before stamping takes place. This cam is pivotally mounted at its outer end on an arm 79 projecting below the guide rail from bracket 6. The inner end of the cam is loosely connected to a screw 80 that is threaded in a nut 81 rotatably mounted in bracket 6. By turning this nut, the inner end of the cam can be adjusted transversely of the table.

Mounted on the slide midway between the two chucks is an inking member which includes a circular disc or platen 83 rigidly mounted on the upper end of a shaft 84 journaled in a bearing 85 mounted on the center of the slide. As the slide moves back and forth, the platen is inked with gold, silver or other ceramic color by a pair of inking rolls 87 mounted above it. The front ends of the rolls are journaled in bearings 88 attached to a vertical plate 89 mounted on the front guide rail 3. The opposite ends of the rolls are journaled in bearings 91 mounted on a plate 92 supported above the table by the side flanges of an upright frame 93 mounted on top of the table. The desired color may be supplied to the inking rolls from small tanks 94 supported above them. The color is forced out of small openings in the bottoms of the tanks at the desired rate by air pressure which is supplied to the tanks in any convenient manner.

Every time the slide reciprocates, platen 83 is rotated a few degrees by an arm 97 mounted on the upper end of a shaft 98 that is journaled in a bearing 99 in the top of the table. The free end of the arm may be bifurcated to straddle any one of a series of pins 101 projecting downwardly from a collar mounted on the lower end of platen shaft 84. If desired, the platen can be held stationary while the arm is being swung back to its original position, by a spring-pressed dog 103 (Fig. 5) pivotally mounted on the bottom of the slide with its free end provided with a lateral notch that receives one of the pins 101.

The lower end of shaft 98 on which the arm is mounted is connected to one end of an arm 105 the opposite end of which is pivotally connected by a link 106 to the upper end of a lever 107. The central portion of the lever is pivotally supported by a bearing 108 mounted on the side of a vertical member 109. The lower end of the lever carries a roller 111 that projects into a cam groove 112 in a plate 113 that is rigidly mounted on one side of a cam disc 114. This disc is rigidly mounted on cam shaft 16. As the shaft rotates, the cam groove oscillates the lever and thereby swings the platen arm 97 back and forth to periodically index the platen.

Disposed directly above the inking platen and also directly above one of the chucks when the slide is at either end of its path of travel are a pair of stamps 115 and 116 for decorating the upper surfaces of ware mounted on the chucks. Each of these stamps is supported by a rod 117 that is detachably connected at its upper end to the lower end of a rod 118 that is adjustable vertically in a vertical tube 119. For this purpose the upper end portion of each rod 118 is threaded in a nut 121 that can be turned by a handle 122. The lower end of the nut has a flange underlying a cap 123 that is screwed on the upper end of the tube so that the nut can not move away from the tube. The tubes are vertically reciprocable in bearings 124 projecting from the front plate 125 of the frame.

Each of the tubes is reciprocated, in order to reciprocate the stamp it supports, by a crank. The crank includes a link 127 that is pivotally

connected to the side of the tube and to a crank disc 128. The disc is rigidly mounted on one end of a shaft 129 that is journaled in frame 93 and its front plate 125. This shaft preferably is made in two parts normally connected together by a manually operable clutch 130 (Fig. 3). The rear end of the shaft carries a sprocket 132 which is connected by a chain 133 to a large sprocket 134 journaled in the lower portion of the frame. The chain between the two upper sprockets passes under an idler sprocket 135 that is adjustable vertically in the back of the frame so as to keep the chain taut. It will be seen that as the large sprocket is oscillated, the smaller sprockets likewise will be oscillated and the cranks will therefore raise and lower the stamps.

To oscillate the large sprocket, it is pivotally connected by a link 137, that extends down through the top of the table, to the free end of a horizontal lever 138 the opposite end of which is oscillatably mounted in a bearing 139 attached to a vertical member 140. The central portion of this lever carries a laterally projecting roller 142 that extends into a cam groove in cam disc 114. This groove is the same shape as cam groove 14, and is directly behind it. In fact, it is possible to operate both of the main levers from a single cam groove. Cam 114 and lever 138 oscillate the large sprocket 134 through a 90° arc. This sprocket has approximately four times as many teeth as either of the smaller sprockets 132 so that the latter will be oscillated about 360°. Thus, the large sprocket may have eighty teeth while each of the small sprockets may have twenty-one teeth. This makes it possible to get the cranks and stamps in motion before much force is applied to the stamp. It will be seen that when the upper end of link 137 has traveled 45° from either the upper or the lower end of its path, crank links 127 will be in their lower position and the stamps will therefore be in engagement with inking platen and ware on one of the chucks. Continued movement of link 137 for the other 45° of the arc will raise the stamps to their original position. The same thing happens when the link moves in the opposite direction. In Fig. 1 the upper end of link 137 is shown in its upper position, so the stamps are raised. In Fig. 2 the large sprocket 134 has been rotated 45°, so the stamps are in their lower or stamping position. By the time the sprocket has turned another 45° in the same direction the stamps will be brought by their actuating cranks to their upper position.

If only the center or the brim of the ware is to be decorated by a single stamping member, the latter can be a unitary stamp rigidly mounted on the lower end of rod 117. On the other hand, if decorations are desired for both the center and brim of the ware, it will save time to stamp both decorations simultaneously. This can be done in accordance with this invention, as shown in Figs. 2, 7, and 8, by providing each stamping member with a center stamp 150 encircled by a brim stamp 151. The center stamp is mounted on the bottom of a disc 152 which is rigidly mounted on the lower end of rod 117 so that the lower surface of the stamp always descends to the same level, whether it is being inked or is stamping a piece of ware. Slidably mounted on rod 117 above the disc is a metal plate 153 that is normally held in its lower position on the rod, as shown in Fig. 7, by means of a coil spring 154 encircling the rod and compressed between the plate and a collar 155 on the rod above it. The lower surface of the plate 153 carries the annu-

lar brim stamp 151 that encircles the disc 152 and the center stamp 150. The brim stamp has an inner annular recess into which the disc 152 extends so that it overlies a substantial portion of the brim stamp. The bodies of the stamps are made of deformable resilient material, such as sponge rubber.

When the stamping member is raised and also when it engages the inking platen, the lower surface of its center and brim stamps lie in a common horizontal plane, as shown in Fig. 7, because spring 154 urges plate 153 down to its lowest position. The two stamps 150 and 151 thus engage the inking platen flat and with the same pressure for uniform inking of their surfaces. However, in stamping a piece of ware, such as dinner plate 41 or the like, the two stamps will engage the ware at different levels. If their decorating surfaces lie in the same plane, the brim stamp would be so highly compressed by the plate brim that the brim design would be smeared and indistinct. To avoid this, the plate 41 is supported with the flat upper surface of its bottom at substantially the same level as the top of the inking platen so that the center stamp 150 will engage the plate 41 with just the right amount of pressure, and the downward movement of the brim stamp 151 is restrained in order to elevate it relative to the center stamp. This restraint is effected by vertical pins 151 mounted on top of slide 4 around the chuck. As a stamping member descends toward an underlying piece of ware, its plate 153 strikes the tops of these pins by which further movement of that plate is prevented just as the outer edge of the brim stamp engages the brim of the ware, but rod 117 and the center stamp continue to descend a short distance farther so that disc 152 secured to a rod presses the inner portion of the brim stamp downwardly. This action presses the decorating surface of the brim stamp down against the inclined brim of the ware as the center stamp strikes the center of the ware, as shown in Fig. 8. The outer stamp 151 thus engages the ware with substantially the same pressure as the inner stamp 150. When the stamping member is raised again, the plate 153 is returned to its lower position on rod 117 by the spring 154.

In the operation of this machine, an operator is stationed at each end of the table and as slide 4 is moved toward one of them he places a piece of ware on the adjacent chuck 27. Centering fingers 50 are held open at this time by cam bar 67, and the stamping members are in their upper position. Referring to Fig. 1, as cam 15 continues to rotate in a clockwise direction, the lever 9 is swung to the right which moves the slide to the right on its guide rails. As soon as roller 65 of the centering device runs off the inner end of cam 67 the centering fingers 50 are swung inwardly by spring 69 and the ware is thereby centered on the chuck. Immediately following this, slide valve 37 at the front of the table is opened so that vacuum is applied to the chuck to hold the ware in centered position thereon. The slide carries the chuck under stamping member 115 and then stops while cam 114 and lever 138 cause both stamps to descend in unison. As shown in Fig. 2, stamping member 115, which previously has been inked, stamps a decoration on the ware beneath it in the manner illustrated in Fig. 8, but stamping member 116 engages the inking platen by which color is applied to it. The platen 75 received color from rolls 87 as it passed under

them. The shape of cam groove 112 is such that it causes arm 97 to rotate platen 83 a few degrees while the stamps are descending, and then a few more degrees after the stamps have started to rise again. The ware which previously was decorated by stamping member 116 is carried by the slide to the workman at the right end of the table where it is removed from the chuck and is replaced by an undecorated piece.

Continued rotation of cam 114 causes the stamping members to be raised again, after which the slide is moved by lever 9 back to the left to carry the right-hand chuck under stamping member 116 and to locate the inking platen under stamping member 115. When the stamping members descend in order to ink one and to press the other against the right-hand plate, the decorated left-hand plate is removed and replaced by another plate by the workman at the left end of the table.

It will thus be seen that this machine can operate very rapidly and that it has a high capacity, because a piece of ware is moved under one stamp every time the slide moves a decorated piece away from the other stamp. Also, by stamping both center and brim simultaneously, the performance of a second stamping operation on the same ware is eliminated and proper positioning of the two decorations relative to each other is assured.

In the following claims reference is made to "horizontal" and "vertical" elements and movements, but that is done only for convenience in locating the different elements relative to one another, since it will be understood that the invention is the same whether the stamps reciprocate vertically, horizontally or at an inclination.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. In a potteryware decorating machine, a pair of independently mounted coaxial stamps, a support for the outer stamp projecting laterally beyond it and provided with a central opening, a support for the inner stamp slidably mounted in said opening, one of said supports being slidably axially relative to the other to move the adjoining stamp from inking position to stamping position, means associated with said supports for periodically holding them with the decorating surfaces of the two stamps in substantially the same plane for inking, and means adapted to be engaged by the projecting portion of the support for the outer stamp to limit its movement toward stamping position relative to the movement of the center stamp.

2. In a machine for decorating the inside of concave potteryware, a pair of independently mounted coaxial stamps, a support for the outer stamp provided with a central opening, a support for the inner stamp slidably mounted in said opening, means for moving one of said supports vertically relative to the other to move the adjoining stamp from inking position to stamping position, means for limiting the distance that said outer support can approach the ware being decorated, a spring for moving said one support in the opposite direction to return said adjoining

stamp to inking position, the decorating surfaces of the two stamps being in substantially the same plane when in inking position and the decorating surface of the inner stamp being below the outer stamp when in stamping position, the outer stamp being provided with an inner annular recess, and a circular plate carried by said inner stamp support and projecting into said recess for engaging the underlying portion of the outer stamp for pressing said portion downward during stamping to slant the decorating surface of the outer stamp down toward the axis of the stamps.

3. In a machine for decorating the inner surfaces of concave potteryware, a horizontal plate provided with a central opening, a sleeve rigidly connected to the plate around said opening and extending upward therefrom, an annular flexible stamp secured to the bottom of the plate around said opening and provided with an inner annular recess, a post slidably mounted in said sleeve, a center stamp carried by the lower end of the post, means for reciprocating the post in the sleeve to move the inner stamp between inking and stamping positions, means separate from the ware being decorated for holding said plate stationary when the inner stamp is moved down to stamping position, and stamp flexing means carried by the post and projecting into said annular recess for engaging the underlying portion of the annular stamp for flexing the stamp when the inner stamp is moved between said positions, the lower surfaces of the stamps being in substantially the same horizontal plane when in inking position but the lower surface of the center stamp being below the annular stamp when in stamping position, and the lower surface of the annular stamp slanting down toward the axis of the stamps when they are in stamping position.

4. In a potteryware decorating machine, a support for ware being decorated, a pair of coaxial stamps above said support with their lower surfaces normally disposed in substantially the same plane for inking, means for vertically reciprocating said stamps together, the inner stamp being movable downwardly relative to the outer one, and means around said support for limiting the downward movement of the outer stamp whereby the inner stamp projects below the outer stamp.

5. In a potteryware decorating machine, a support for ware being decorated, a pair of coaxial stamps above said support, the outer stamp being movable axially relative to the inner one, resilient means normally holding the outer stamp in lowered position with the lower surfaces of the stamps in substantially the same plane for inking, means for vertically reciprocating the stamps together, and means disposed at circumferentially spaced points around said support for limiting the downward movement of the outer stamp whereby the inner stamp continues to move downwardly to a lower position for stamping.

6. A potteryware decorating machine comprising a support for ware being decorated, a pair of coaxial decorating stamps in a plane above said support, means for vertically reciprocating the stamps, the inner stamp being movable downward relative to the other, resilient means normally holding the outer stamp in the plane of the inner one for inking, and means beside the ware support for limiting the downward movement of the outer stamp to position the two stamps at different levels.

7. A potteryware decorating machine, compris-

ing a support for concave ware being decorated, a pair of coaxial decorating stamps above said support with their lower surfaces normally in the same horizontal plane for inking, means for moving the stamps downward together, and means for arresting downward movement of the outer stamp while the inner stamp continues to move downward a short distance to stamp the center of ware on said support, whereby the pressure of the outer stamp against the marginal portion of the ware can be controlled.

8. A potteryware decorating machine, comprising a support for concave ware being decorated, a pair of coaxial decorating stamps above said support with their lower surfaces normally in the same horizontal plane for inking, means for moving the stamps downward together, and means for arresting downward movement of the outer stamp while the inner stamp continues to move downward a short distance to stamp the center of ware on said support, whereby the

pressure of the outer stamp against the marginal portion of the ware can be controlled, and means movable with the inner stamp for flexing the outer stamp.
